UNITED STATES PATENT OFFICE

ROBERT S. BLAIR, OF STAMFORD, CONNECTICUT

NONSLIPPING DEVICE

Application filed October 8, 1923. Serial No. 667,122.

This invention relates to non-slipping devices and with regard to its more specific features to such devices adapted to prevent slipping in pre-determined directions of implements to which they are applied.

One of the objects of the invention is to provide a device of the above nature practical and efficient and capable of operating in a highly dependable manner. Another object is to provide a device of the above nature of simple and inexpensive construction. Another object is to provide a practical art whereby devices of the above character may be made in a convenient manner with simple apparatus. Other objects will be in part obvious or in part pointed out hereinafter.

This application is in part a continuation of my application for non-slipping device filed March 24, 1919, Serial No. 284,620, later 20 patented under the Number 1,469,766, Oct. 9, 1923.

The invention accordingly consists in the features of construction, combinations of elements, arrangements of parts and in the several steps and relation and order of each of the same to one or more of the others all as will be illustratively described herein, and the scope of the application of which will be indicated in the following claims.

30 In the accompanying drawing in which are shown one or more various possible embodiments of the several mechanical features of this invention:

Figure 1 shows in enlarged detail and in 35 both plan view and section a portion of material adapted for use in my invention.

Figure 2 shows a portion of the handle of a tennis racket and a non-slipping covering partially applied thereto.

40 Figure 3 is a view similar to Figure 2 showing a different form of covering.

Figure 4 is an end view of the covering shown applied to the tennis racket in Figure 3.

45 Figure 5 shows a non-slipping device similar in construction to that shown in Figure 4 applied to a fountain pen.

Figure 6 is a plan view of a portion of a die member in enlarged detail adapted for use in making non-slipping material.

50 Figure 7 shows in enlarged detail a piece

of material in operative relation to the die, and

Figure 8 shows this material at a later stage in the process of its manufacture.

Similar reference characters refer to similar parts throughout the several views of the drawing.

Referring now to the drawing in detail, in Figure 1 there is shown a portion of material which comprises the skin of an aquatic creature, in this instance the skin of a shark. This skin has on its outer surface bony spine-like projections indicated at 10 which extend outwardly therefrom and are all inclined in the same direction. These spiny projections are minute in the order of about one-hundredth of an inch in length being thus barely visible and they cover the shark skin with considerable density as may be seen from Figure 1 which is of course in greatly enlarged detail. These projections therefore form what might be termed a "nap" permitting, for example, ready passing of the hand thereover in one direction, but offering great resistance to stroking in the opposite direction. A covering of this material upon any implement therefore with the inclined spines all aimed in the same direction would permit slipping of the implement upon surfaces with which it comes into contact, in the direction of the inclination of the spines, but would effectively prevent such slipping in the opposite direction.

Referring now to Figure 2, there is shown a covering of this material of shark skin or the like applied to the handle 11 of a tennis racket. In an implement such as a tennis racket it is highly desirable that the handle afford the player such a grip that rotation of the handle in the hand is avoided. Such rotation is likely to occur with consequent deflection of the tennis ball, particularly when the ball is struck with the side portion of the racket near the rim thereof. As has been above explained a covering of material similar to shark skin having the spines projecting all in the same direction, would provide for such a grip as would permit rotation of the handle in one direction in the hand, but prevent such rotation in the opposite direction.

tion. The covering shown in Figure 2 therefore is applied in two strips 12 and 13 conjointly wound in parallel about the handle of the tennis racket, the spines of one strip being inclined in one direction and those of the other strip in the opposite direction. In this manner the covering affords the player such a grip upon the handle as to prevent rotation thereof in the hand in either direction. The ends of the strips 12 and 13 may be secured as by a suitable ring 14 at the end of the handle and by similar means, if desired, at the other end of the covered portion. In order to more securely fix the covering to the handle the strips may be cemented thereto if this is found desirable.

Referring now to Figure 3, there is shown a different form of non-slipping covering comprising shark skin or the like applied to the handle 15 of a tennis racket or the like. This covering comprises a pair of sections 16 and 17 of the shark skin having their spines inclined in opposite directions and secured to an elastic band or sleeve 18. As shown in Figure 4 the sections or strips 16 and 17 are secured to the elastic member 18 at their edges 19 and 20 and 21 and 22 respectively. When the elastic member 18 is slipped over the end of the handle 15 it stretches from its normal position shown in Figure 4 to snugly embrace the handle and contact the entire inner surface of the strips 16 and 17. The strips 16 and 17 do not extend completely around the handle, but leave at either side exposed portions 18^a of the member 18. The shark skin strips are thus conveniently and dependably mounted in position upon the handle. The spines of the two sections of the skin being inclined in opposite directions about the handle are adapted to resist rotation thereof in either direction in the hand. If desired suitable rings, such as 19, may be employed to encase the end portions of the covering.

In Figure 5 there is shown a non-slipping device similar in construction to that of the covering of Figures 3 and 4 applied to a fountain pen for the purpose of retaining the pen in the pocket. There is provided an inner sleeve or band 20 of elastic material adapted to snugly grip the shaft-like shank of the pen, and secure to this member 20, substantially in the manner in which the parts 16 and 17 are secured to the elastic member 18 of Figure 4, are a pair of sections 21 and 22 of non-slipping material. These sections 21 and 22 may be of shark skin and in this instance the spines of each section are inclined in the same direction, namely, upwardly along the shank of the pen. It will be seen that the pen may be readily slipped down into the pocket, but will be prevented from slipping out therefrom by the spiny projections of the parts 21 and 22 engaging the surfaces of the walls of the pocket. The device may

be positioned at any convenient place along the length of the pen being herein shown positioned at the lower end of the cap portion 23 thereof.

As has been mentioned above, the parts 21 and 22 may be of shark skin, but they are preferably made of a material formed to have characteristics of shark skin and more appropriate for use on an implement such as a fountain pen. For example, it might be desirable that the parts 21 and 22 forming the non-slipping surfaces be of gold or a suitable gold alloy. The appearance of this latter form of surface is far preferable to that of shark skin and the minute spiny projections of shark skin are reproduced upon the surface of thin bands of a suitable metal such as gold preferably as will now be described. It may here be noted, moreover, that the term "metal" is used throughout with a broad meaning to comprehend any substance having characteristics adapting it for employment in embodying or carrying on the invention as herein set forth.

In Figure 6, there is shown in enlarged detail a plan view of a portion 24 of a die having a multitude of preferably regularly spaced minute recesses 25. These recesses 25 are preferably substantially cone-shaped as is shown in the sectional view of the die in Figure 7 and each preferably has a cross-section substantially the shape of the spiny projections of the skin of a shark. In Figure 7 there is shown a thin strip 26 of gold or other suitable metal placed upon the top of the die 24. The gold has appreciable malleability and by suitably working the upper surface thereof, as by rolling it with a roller 27 and with considerable downward force the metal of the gold strip 26 is caused to flow into the minute recesses 25. The result of this process is that there are formed upon the surface of the strip 26 a multitude of vertical minute projections 28 as shown in enlarged detail in Figure 8. These projections 28 are closely spaced and each resembles in contour the spiny projections of a shark skin raised to vertical position. Now by passing a roller, as 29, lightly over these projections in the direction of the arrow as indicated in Figure 8, the projections are all inclined in the same direction as shown at 28^a and the gold strip is thus provided with a surface similar to the surface of the shark skin shown in Figure 1. From the strip 26 are then formed and shaped parts similar to those marked 21 and 22 in Figure 5 and these are secured to an elastic band 20 at their edges as shown in Figure 4 in any desired manner. It will be seen that a device made as above described provides an attachment for a fountain pen or the like which has the desired neatness and attractiveness of appearance. The spiny projections of the surfaces of the gold act in the manner of those of shark skin 130

to prevent the pen from slipping out of the pocket. The art of making these devices is one which is conveniently carried on with simple apparatus.

As many possible embodiments may be made of the mechanical features of the above invention and as the art herein described might be varied in various parts all without departing from the scope of the invention, it is to be understood that all matter herein set forth or shown in the accompanying drawings is to be interpreted as illustrative and not in a limiting sense.

I claim as my invention:—

1. In a device of the class described, in combination, an endless band of elastic material, and a member having a plurality of minute inclined projections secured at spaced points to the outer surface of said band, adapted to form a non-slipping surface about a member upon which said band is placed.

2. In a device of the class described, in combination, an endless band of elastic material, and a plurality of members secured to the outer surface of said band at spaced points each having a multitude of minute projections adapted to prevent slipping upon surfaces with which they come into contact.

3. In a device of the class described, in combination, an elastic member adapted to embrace a pocket implement, and a metal strip secured at spaced points to the outer surface of said member and having an outer surface comprising a multitude of inclined pointed projections.

4. In a device for providing a non-slipping outer surface, in combination, an elastic supporting member axially elongated with respect to its diameter adapted to be fitted over and grip tightly an elongated part and a pair of axially elongated members mounted upon said first member and opposite one another in a circumferential direction, each of said last members having an outer surface formed of a multitude of minute spines and said spines on each member being inclined against the direction of the tendency of relative movement of the surrounding surfaces in use.

5. In a device for providing a non-slipping outer surface, in combination, an elastic sleeve axially elongated with respect to its diameter and adapted to be fitted over and tightly grip an elongated portion of an implement, and a pair of members mounted upon said sleeve and opposite one another in a circumferential direction, said last members each being provided on their outer surfaces with a multitude of minute spines and said spines upon each of said members being inclined in a direction opposite to that of the tendency of relative movement of the contacting surfaces for the use of the implement.

6. In a device for providing a non-slipping outer surface, in combination, an elastic sleeve axially elongated with respect to its

diameter and adapted to be fitted over and grip tightly an elongated portion of an implement, and a pair of axially elongated pieces of sharkskin secured to said sleeve upon opposite sides thereof and substantially opposite one another, the spines on each of said pieces of sharkskin being inclined in a direction opposite to that of the tendency of relative movement of outer contacting surfaces in the use of the implement.

7. In a device for providing a non-slipping outer surface, in combination, an elastic band axially elongated with respect to its diameter adapted to be fitted over and tightly grip an elongated portion of an implement, and a pair of axially elongated pieces of sharkskin secured to said sleeve on opposite sides thereof and substantially opposite one another and spaced one from another on both of their axially extending edges whereby said elastic sleeve is permitted to expand between said pieces of sharkskin on opposite sides of the implement, the spines on each of said pieces of sharkskin being inclined in a direction opposite to that of the tendency of relative movement of outer contacting surfaces with the implement in use.

In testimony whereof, I have signed my name to this specification this 5th day of October, 1923.

ROBERT S. BLAIR.
